[57] CLAIM

The ornamental design for paper product, as shown and described.

DESCRIPTION

FIG. 1 is a top front perspective view of a paper product, showing our new ornamental design.

FIG. 2 is a top plan view of the paper product shown in FIG. 1, the opposite (bottom) side view being a mirror image thereof.

FIG. 3 is a frontal elevational view of the paper product shown in FIGS. 1 and 2, the opposite (rear) elevational view being a mirror image thereof.

FIG. 4 is a side elevational view of a paper product shown in FIGS. 1, 2 and 3, the opposite side elevational view being a mirror image thereof; and,

FIG. 5 is a top plan view of the paper product, showing another embodiment of our new ornamental design, the opposite (bottom) side view being a mirror image thereof, all other views thereof being substantially similar to those shown in and described in FIGS. 1, 3, and 4.

The dashed lines showing a roll are for illustrative purposes only and form no part of the claimed design. It is to be understood that the design pattern shown in FIGS. 1-4 continues throughout a length and a width of the paper product, including a portion of the product comprising the roll shown in dashed lines. The paper product is shown broken away to indicate that the paper product, including the portion comprising the roll, has indeterminate width. The broken lines are for illustrative purposes only and form no part of the claimed design.
